UNITED STATES PATENT OFFICE.

CHARLES C. HALL, OF KALAMAZOO, MICHIGAN.

PACKING.

Application filed July 16, 1923. Serial No. 651,884.

To all whom it may concern:

Be it known that I, CHARLES C. HALL, a citizen of the United States, residing at the city and county of Kalamazoo, State of Michigan, have invented certain new and useful Improvements in Packings, of which the following is a specification.

This invention relates to improvements in packings.

10 The main object of the invention is to provide an improved packing which is especially well adapted for high pressures and temperatures and is self-lubricating and very durable.

15 Further objects, and objects relating to structural details, will definitely appear from the detailed description to follow.

I accomplish the objects of my invention by the devices and means described in the 20 following specification. The invention is clearly defined and pointed out in the claims.

A structure which is a preferred embodiment of my invention is clearly illustrated 25 in the accompanying drawing, forming a part of this application, in which:

Fig. I is a plan view of a thin sheet of metal or metal foil such as I employ in my improved packing, no regard being had 30 however to dimensions.

Fig. II is a plan view of the sheet crumpled and crinkled and coated with a lubricant.

Fig. III is an end elevation illustrating 35 one of the steps of manufacture, the thickness of the metal being greatly exaggerated for convenience in illustration.

Fig. IV is a cross section through my improved packing in cylindrical form, the 40 thickness of the material being greatly exaggerated for the purpose indicated.

Fig. V is a cross section through my improved packing compacted to a rectangular cross section, the material being shown of 45 exaggerated thickness for convenience in illustration.

In the drawing similar reference characters refer to similar parts throughout the several views.

50 Referring to the drawing, I provide thin sheets of metal or metal foil 1 which are crumpled or crinkled and coated with lubricant. A high heat resisting oil and powdered or flaked graphite in the form of a

paste is very satisfactory. I have only illustrated one sheet to illustrate this step but it will be understood that I employ sheets of thin copper and sheets of thin aluminum, the copper being indicated at 2 and the aluminum at 3. These sheets are formed of 55 copper and aluminum alloys or at least alloys which are dominated by copper and aluminum. The sheets are preferably about 1/1000 of an inch in thickness, both aluminum and copper sheets being 60 preferably annealed after rolling.

The coating of lubricant is in practice applied before the crumpling operation. This crumpling produces very irregular surfaces, no attempt being made in the drawing to illustrate this irregularity with exactitude. The coated and crumpled sheets are then rolled into a scroll form with the copper at the outside. The rolled sheets 70 are then compacted into the desired cross section round, as indicated in Fig. IV, or into rectangular cross section as shown in Fig. V. The lubricant is held in pockets in and between the rolled sheets.

75 My improved packing is adapted to be 80 used as an ordinary packing by bending around a shaft or compressing into a stuffing box by means of a gland or forcing into place by the tapering or ramming tools.

85 My improved packing has great tensile strength and is highly desirable for use where high temperatures and pressures are present.

90 My improved packing is particularly well adapted for use as a "junc" or "throat" ring, either ahead of the softer packing to prevent the latter being forced out of the box by compression or as a final ring serving the same purpose when the gland does not fit around the rod. The lubricant is effectively 95 held within the packing so that it is self-lubricating and very durable and is not likely to cut or score the moving parts. It is very economical in comparison with the cast brass follower rings which are frequently employed.

100 It is easy to apply as it is not necessary to detach cross heads or brackets or the like as it can be applied in the form of a strap by simply wrapping around the rod and cutting off the desired 105 length. When made in the form of pressed rings the rings may be split and slipped over the rod.

Having thus described my invention, what I claim as new and desire to secure by Letters Patent, is:

1. A packing comprising a sheet of aluminum and a sheet of copper crumpled, coated with lubricant, superimposed and rolled together into a scroll so that there is copper at the outside, and compacted.

2. A packing comprising a sheet of aluminum and a sheet of copper crumpled, coated with lubricant, and rolled together into a scroll.

In witness whereof I have hereunto set my hand and seal.

CHARLES C. HALL. [L. S.]
